F. U. S. GILBERT

METALLIC RECEPTACLE

Filed Dec. 14, 1923

FIG. 1.

FIG. 2.

FIG. 4.

INVENTOR.

Frank U. S. Gilbert
BY
John A. Bonnhardt

ATTORNEY.

UNITED STATES PATENT OFFICE.

FRANK U. S. GILBERT, OF BAY VILLAGE, OHIO.

METALLIC RECEPTACLE.

Application filed December 14, 1923. Serial No. 630,648.

To all whom it may concern:

Be it known that I, FRANK U. S. GILBERT, a citizen of the United States, residing at Bay Village, in the county of Cuyahoga and 5 State of Ohio, have invented certain new and useful Improvements in Metallic Receptacles, of which the following is a specification.

This invention relates to improvements in 10 metallic receptacles, having for an object to provide a structure which will permit the use of the ordinary packing machinery thus increasing the output and at the same time prevent injury to the labels usually placed 15 upon a can or receptacle prior to the packing operation.

It is also an object to provide a metallic receptacle or can of this character in which the main body portion between the extreme 20 ends will be spaced from the table or other support to such an extent as will prevent contact as between said table and a label carried by the receptacle, thus preventing tearing or otherwise injuring said label.

25 In order that the invention and its mode of operation may be readily understood by persons skilled in the art, I have in the accompanying illustrative drawings and in the following detailed description based 30 thereon set out one possible embodiment of the same.

In these drawings:

Fig. 1 is a view in which the can or receptacle is shown in full lines in one position and in dotted lines in a position it assumes as a result of being acted upon by the usual packing machinery.

Fig. 2 is a detail vertical sectional view of 40 a portion of a receptacle constructed in accordance with my invention.

Fig. 3 is an end view of the structure as shown in Figure 2, and:

Fig. 4 is a side elevation partly in section of the usual constructed receptacle, bringing 45 out the fault of this construction.

It is the usual practice in boxing or packaging metallic receptacles or cans of this nature, to convey them to a certain point at which they are arranged in tiers until a pre-determined number have been so arranged. 50 At this point the assembly is moved in the direction of the arrow as indicated in Figure 1 and into a box or the like in which they are shipped. At the present time this 55 operation is necessarily accomplished by

hand, due to the fact that the structure is such as that shown in Figure 4 and the plain or smooth end must be lifted from the support or table, if tearing of the label in the sliding of the cans into the box is to be 60 eliminated. This results in the boxing of a very small number of cans due to the fact that it is a slow operation and also requires the services of an unusually large number of 65 workers. There is in existence machinery which is capable of accomplishing speedy and accurate packing of the cans, this machinery taking care of all of the several operations necessary. However, with the use of this machinery with cans as at present 70 constructed, the result is that all of the labels upon the lower tier of cans would be torn and it is appreciated that this is very undesirable.

I eliminate this fault through providing 75 a slip cap with a head as shown in Figure 1, the result being that the body portion of the can bearing the label is spaced above the table or support sufficiently to permit of sliding of the can or receptacle upon the 80 table without any contact whatever as between the label and the support.

In the accompanying drawings throughout which similar characters of reference 85 designate similar parts, I have shown a can including a body portion 5 preferably circular in cross-section and having an annular radial outwardly extended bead 6 at its closed end, the open end 7 being shouldered as at 8 and turned inwardly at the extreme 90 end portion 9, whereby to facilitate the placing of a slip closure 10 thereover and provide a continuous smooth surface for a label.

This cap 10 as clearly shown in Figure 2 95 includes a head or end portion 11 provided with an annular longitudinally extending flange or collar portion 12, which snugly takes over the end of the can body in the usual manner. Arranged at the juncture of 100 this head portion 11 and the collar 12 is an annular radial bead 13, which is preferably co-extensive with the bead 6 at the opposite end of the receptacle. These two beads 105 contact to space the intermediate body portion sufficiently above the table or support upon 110 which it is arranged to permit application of the usual label 14 about the body and at the same time prevent contact with the table or support, with the result that sliding or

otherwise moving the receptacle along the support may be accomplished without injury to the label.

By reference to Figure 1 of the accompanying drawings, it will be quite apparent that these beads 6 and 13 in addition to providing means for spacing the attached label from the table or support, also serve to guide the label accurately upon the body portion for pasting or securing it thereto.

I claim:

1. In a metallic receptacle of the character described a body portion, having an open end, an annular radial outwardly extended bead at the closed end, a slip cap for the open end, and an annular radial outwardly

extended bead carried by the cap whereby to space the body portion from a support and prevent injury to a label arranged upon the body portion.

2. The combination with a metallic receptacle having an open end, and an annular radial outwardly extended bead at its closed end; of a slip cap for the open end, and an annular radial outwardly extended bead carried by the cap and adapted to contact with the first named bead to space the intermediate portions from a support whereby to protect a label from injury.

In testimony whereof, I affix my signature.

FRANK U. S. GILBERT.
